CLOSURE STRUCTURE FOR CONTAINERS FOR GRANULAR PRODUCTS

Horace P. Abbott, Old Greenwich, Conn., assignor to Lever Brothers Company, New York, N.Y., a corporation of Maine

Filed May 5, 1964, Ser. No. 364,919
3 Claims. (Cl. 222—543)

This invention relates to containers and, more particularly, to a novel and improved closure structure for containers, and principally for containers for granular materials.

Granular products for general consumer use, such as granular forms of soaps or detergents for dish washing or clothes washing purposes, are usually packaged in cardboard cartons. Such cartons are opened by partially or completely removing the upper end of one edge or one end of the top, the removable part of the box generally being outlined with perforations or score lines to facilitate its removal. While in some boxes the piece removed remains hingedly secured to the box, there is no way of effectively closing and sealing the box to prevent the contents from inadvertently being spilled while handling or preventing moisture or foreign material from entering. Moreover, the simple opening in the end or top of the box is poorly adapted for the controlled discharge of the granular product therein, inasmuch as the opening is usually overly large and permits the passage of large amounts of the product in a relatively short time. When the user encounters difficulty in dispensing the product, she will often shake the box to increase the flow of the product and frequently thereby dispenses an excessive amount. The use of cardboard boxes for such products, moreover, has the further disadvantage of permitting moisture to reach the contents, if the box becomes wet, thereby sometimes consolidating the product somewhat into large chunks which are not readily or conveniently removed from the box, and even ruining the product.

Accordingly, I have provided, in accordance with the invention, a novel and improved container for granular products and, particularly, a closure structure for such a container which enables a granular product therein to be readily dispensed with considerable control by the user over the amount dispensed. Moreover, the closure structure includes a hinged cap which is connected to the container, and the container may be closed and sealed after each use. By connecting the cap to the container, it cannot be misplaced when the container is opened.

More particularly, a closure structure for a container, in accordance with the invention, comprises a tapered nozzle having a relatively large lower opening and means for securing it to a receptacle at its lower end. Preferably, the receptacle for use with the closure structure is in the form of a moisture impervious bottle, for example, a bottle made of polyethylene or other plastic, rather than a cardboard box or the like. The nozzle and cap are also, preferably, made of plastic, such as by molding.

The walls of the nozzle taper upwardly and inwardly toward a smaller outlet opening at its upper end which lies in a plane disposed at an angle to the axis of the nozzle. An inturned lip is provided about the perimeter of the opening and an undercut is formed immediately below the lip. The outlet opening of the nozzle receives a closure cap, which may either be formed integrally and hingedly connected to the upper end of the nozzle or may be formed separately and then connected to the nozzle such as by a snap-in arrangement. The cap includes a planar body portion which overlies and projects beyond the edge of the nozzle outlet opening and, further, includes a portion extending substantially beyond the upper

2

most part of the inclined opening, thereby facilitating the removal of the cap.

Projecting from the planar body portion of the cap is a rib having an outwardly extending bead at its outermost end, the rib being receivable in the outlet opening of the nozzle and engageable with the inturned lip of the opening and the bead being receivable in the undercut adjacent the nozzle inturned lip to hold the cap on the nozzle.

10 Adjacent the uppermost portion of the nozzle, that is, the portion lying adjacent the uppermost edge of the inclined upper opening, is an inturned wall portion which forms an angle with the longitudinally adjacent wall portion of the nozzle. This inturned portion of the nozzle wall, together with the inclination of the outlet opening of the nozzle, provide improved and controlled flow of granular material out of the container. More particularly, the nozzle is tapered and thereby guides the granular material smoothly toward the relatively restricted orifice or opening therein. By providing a relatively small opening for the material to be dispensed from the receptacle, the amount which can flow from the receptacle during a given period of time is considerably reduced as compared to the amount which can flow through the 15 large openings provided in present containers for such products. Accordingly, the problem mentioned above of the sudden outflow of large amounts of material is substantially overcome. Moreover, the inturned portion adjacent the uppermost part of the discharge opening 20 serves as a dam, thereby confining or entrapping a marginal layer of the material directly adjacent the opening. Accordingly, the granular material flows out of the container by sliding along this entrapped marginal layer and is somewhat retarded thereby, especially when the container is tilted at smaller angles. Such sliding provides 25 considerably greater control over the outflow rate than the control that can be had when the material flows over the relatively smooth surface of a container wall.

An important feature of the invention is the provision 30 on the planar body portion of the cap of an extended portion adjacent the uppermost or outermost part of the discharge opening which may be engaged by a finger or an implement to lift and open the cap. In addition, the cap is hingedly connected to the nozzle at the lowermost or 35 innermost edge of the top opening. Accordingly, the user is naturally induced by the geometry and the structure of the nozzle and cap to tilt the receptacle in a direction such that the material in the container will be discharged over the outermost edge of the opening. When the material has filled the lower and outermost portion of the nozzle adjacent the inturned part thereof, thereby creating a marginal layer of entrapped material, the material then slides over this marginal layer and over the lip of the outlet opening in a curved narrow stream having a fairly large circumferential dimension relative to the opening, the material flowing over a relatively large portion of the circumference of the top opening. The angular orientation or inclination of the opening of the nozzle with respect to the nozzle axis results, of course, in a similar inclination of the opening to the surface plane of the material when it is being poured from the container. The inclination, moreover, is such that the edge of the opening angles away from a vertical plane tangential to the outermost extremity of the opening, thereby facilitating the passage of material over the edge of the opening. In a nozzle having an opening normal to its axis, there is little or no departure of the edges of the opening from a vertical plane when the nozzle is tilted, and, accordingly, 40 such a form of nozzle opening tends to obstruct the outflow of material.

For a better understanding of the invention reference may be made to the following description of exemplary embodiments, taken in conjunction with the figures of the appended drawing, in which:

FIGURE 1 is an elevational view in section taken generally along the axis of a closure structure installed on a bottle, only a portion of which is shown;

FIG. 2 is a plan view of the underside of the cap, as viewed generally along the line 2-2 of FIG. 1;

FIG. 3 is a partial elevational view partly in section, illustrating the top portion of a nozzle similar to that in FIG. 1 and having a cap connected thereto in a manner slightly different from the attachment of the cap in the embodiment of FIG. 1; and

FIG. 4 is a view in section on an enlarged scale taken transversely through a cap connecting arrangement for the cap in FIG. 3, the section being taken generally along the line 4-4 of FIG. 3 and in the direction of the arrows.

Referring to FIG. 1, the closure structure 10 is installed on a bottle 12, only the upper portion of which is illustrated. The bottle 12 may be of any suitable shape and size and is preferably made of a plastic such as polyethylene by a suitable molding or casting technique. The upper end of the bottle 12 shown is formed as a frustum and has an enlarged bead 14 which defines an opening 16 through which the product in the bottle 12 is conveyed into the closure structure 10. About the outer perimeter of the bead 14 is an inwardly extending groove 18 which includes a generally axial innermost base portion 20 and a beveled base portion 22 adjacent thereto. The groove 18 is spaced from the uppermost edge 23 of the bead 14, thereby providing an outwardly extending upper flange 24. The edge of the flange 24 is spaced from the plane of the outer surface of the part of the bottle 12 and is conical in shape.

The closure structure 10 comprises a nozzle 26 and a cap 28 connected to the nozzle. The nozzle 26 is conical-shaped, tapering in a direction away from the bottle 12, and includes an inturned lower flange 30 which has a size and shape complementary to that of the groove 18 in the bottle bead 14 and is received therein. More particularly, the inturned flange 30 includes a beveled lower edge 32 which slides along the outwardly extending flange 24 of the bottle bead 14 and cooperates therewith to mutually deflect the bottle and nozzle when the cap structure is installed so that the inturned flange 30 will snap into place in the groove 18. When the flange 30 is in position in the bottle groove 18, the nozzle 26 is substantially permanently attached to the bottle 12 by engagement of the flange 24 over the upper edge of the flange 30. Moreover, the complementary shapes and sizes of the flange 30 and the groove 18 provide a tight seal between the nozzle and bottle.

At the upper end of the nozzle 26 is an outlet opening 34 of substantially smaller size than the opening 16 of the bottle 12, and defined by an inturned flange 36. The flange, and therefore the opening, lies on a plane transecting the axis of the bottle and nozzle at an angle. Thus, the opening includes an uppermost point 38, with respect to a transverse plane normal to the nozzle axis, and a lowermost point 40, all other points on the inturned flange 36 lying between transverse planes through the points 38 and 40. In the zone of the uppermost point 38 on the flange 36, the wall of the nozzle 26 includes an angularly disposed or inturned portion 42.

The cap 28 in the embodiment illustrated in FIG. 1 is formed integrally with the nozzle 26 and includes a relatively narrow connecting extension 48 projecting laterally from adjacent the lowermost point 40 on the outlet opening 34 thereof and, as best shown in FIG. 2, a generally flat, circular body portion 50. The cap 28 illustrated in FIG. 1 is in its open position, and therefore the upper end as illustrated in FIG. 1 actually constitutes the underside of the cap when it is installed on the bottle. On the underside of the cap is a rib

52, which, like the opening 34, is annular. The annular rib 52 includes an outwardly extending bead 54.

The inturned flange 36 at the upper end of the nozzle 26 includes an inwardly extending lip 56 and an undercut immediately below the lip. The cap 28 is installed in the nozzle opening 34 by bending it over and pressing the annular rib 52 into the opening. To facilitate bending the cap into its closed position on the nozzle and, moreover, to provide for bending at the proper location to bring the cap rib 52 into register with the opening, a laterally extending groove 60 is provided on the underside of the extension 48. With the cap 52 in register in the opening 34, the cap is then pressed downwardly into the opening, thereby creating mutual deformation of the lip 56 on the nozzle flange 36 and the flange 54 on the cap bead 52. The flange 54 on the cap bead 52 then snaps into place in the undercut 58 on the nozzle 26, thereby removably securing the cap 28 on the nozzle and providing a tight seal.

Referring now to FIG. 2, the body 50 of the cap 28 is generally circular, but the center of the circle is offset from the center of the annular rib 52 and is therefore offset from the center of the nozzle opening 34. Accordingly, as best shown in FIG. 3, an edge zone 61 of the cap body 50 which lies adjacent the uppermost point 38 of the nozzle outlet opening projects a significant distance beyond the edge of the nozzle. The zone 61 of the cap thus provides a convenient place for engagement by a finger of the user or an implement to lift the cap. Moreover, the features of the cap 28, including its hinged connection to the nozzle, its angular orientation with respect to the axis of the bottle and nozzle, and the offsetting of the body portion from the center of the outlet opening 34 cooperate to clearly indicate to a user that the product is to be poured over the lip at the uppermost point 38 on the nozzle, as will be described in greater detail hereinafter.

Referring to FIGS. 3 and 4, the nozzle 26', cap body portion 50' and the closure arrangement between the nozzle opening 34' and the cap rib 52' are identical to the embodiment of FIGS. 1 and 2. However, a different means for connecting the cap to the nozzle is provided. More particularly, a cap 28' in FIGS. 3 and 4 is molded separately from the nozzle 26', and then is connected to the nozzle by means of a laterally extending boss 70 formed on the nozzle adjacent the lowermost point 40' of the opening 34'. Formed in the upper side 72 of the boss 70, which side lies in the plane of the opening 34', is a recess 74, which, as shown in FIG. 3, is generally trapezoidal at a section taken along a radially extending plane of the nozzle and, as shown in FIG. 4, is generally rectangular in a plane taken transversely through the boss 70. Formed in the side walls of the recess 74 and lying generally parallel to the plane of the upper side 72 of the boss 70 are grooves 76.

The body portion 50' of the cap 28' in FIGS. 3 and 4 includes a narrow extension 78 which has a downstanding boss 80 formed integrally therewith. The boss 80 has a size and shape complementary to the recess 74 in the nozzle boss 70 and includes beads 82 on its opposite sides which are received in the grooves 76 in the recess 74 of the boss 70. Accordingly, the cap 28' in the embodiments of FIGS. 3 and 4 is connected to the nozzle 26' by inserting the boss 80 on the cap extension 78 into the recess 74 in the nozzle boss 70, thereby engaging the beads 82 in the grooves 76.

It is preferred that the connecting arrangement of the cap to the nozzle in the embodiment in FIGS. 3 and 4 be dimensioned so that the force required for complete detachment of the cap 28' from the nozzle 26' will be substantially greater than that required to remove the cap from the nozzle opening 34' to open the container. In this way, the user may retain the cap connected to the nozzle so that the container may be

closed after each use. To facilitate opening the container without detaching the cap from the nozzle, a transverse groove 84 is provided in the upper surface of the cap extension 78 which facilitates bending the cap back upon its removal from the opening 34' in the nozzle 26', so that the product may be dispensed. If desired, the user may alternatively disconnect and discard the cap completely by pulling it out of the nozzle boss 70.

To dispense the granular material contained in the bottle 12, the user first places a finger or implement under or grips the cap zone 61 (adjacent the upper end 36 of the nozzle opening 34) and then pulls upwardly to remove the cap from the nozzle outlet opening 34. The bottle 12 is then tilted over, such that the uppermost point 38 on the nozzle 26 is tilted downwardly. Upon tilting, the material flows from the bottle and travels along the zone of the nozzle longitudinally below the inturned portion 42 (the left side of the nozzle 26 as illustrated in FIG. 1). Upon further tilting of the bottle the material flowing along the aforementioned zone is blocked by the inturned wall portion 42 and builds up and forms a marginal layer adjacent the uppermost end 38 of the opening 34. When additional material moves into the nozzle 26, it flows past the marginally collected layer and over the lip of the opening 34.

As previously described, the angular orientation of the opening 34 facilitates the flow of material through the outlet opening. Moreover, the material flow can be more readily controlled, inasmuch as the angularly disposed portion 42 of the nozzle wall serves as a dam and provides a marginal layer so that material being dispensed flows along this marginal layer. Accordingly, the frictional resistance encountered by material flowing out of the bottle is greater, and changes in the angle of tilting will tend to have a relatively limited effect on the material flow. This is quite unlike the situation wherein a granular material flows along a smooth surface which provides relatively little frictional resistance to the flow of material along it, thereby enabling relatively minor changes in the angular position of the aforementioned surface to cause large changes in the discharge rate of the material.

The improved flow properties, as described above, in a nozzle having an inturned portion 42, which serves more or less as a dam in the nozzle, constitutes one of the significant improvements in packaging for granular materials provided by a closure structure, in accordance with the invention. In addition, a cap is provided which is connected to the nozzle, and therefore is easily replaced on the outlet and cannot be misplaced or lost. A closure structure, according to the invention, thus provides significant advantages over known forms of packaging for granular materials. In addition, the closure structure is readily formed, preferably from a polymer such as polypropylene, by a suitable molding process, the molding being facilitated by molding the nozzle 26 separately from the bottle 12.

It will be understood that the above described embodiments of the invention are merely exemplary. Many variations and modifications thereof will occur to those skilled in the art without departing from the spirit and scope of the invention. All such variations and modifications are intended to be within the scope of the invention as defined in the appended claims.

I claim:

1. A closure structure for a receptacle for granular material, comprising a tapered nozzle having a larger opening at one end and a smaller opening at the other end, said smaller opening being disposed in a plane forming an angle with the axis of said nozzle, and said nozzle having an inturned wall portion adjacent the outermost edge of said smaller opening forming an angle with the adjacent wall portion of the nozzle, and defining a portion in said nozzle wherein material is entrapped when other

material is being dispensed, and a cap for said smaller opening, and means for securing said nozzle to said receptacle including a peripheral groove formed in a rim on the receptacle, said rim on the receptacle having a taper matching and contiguous to the nozzle, said groove including an upper surface lying in a plane substantially perpendicular to the axis of the receptacle and defining a sharp corner with the rim, and a rib formed on the nozzle and receivable in said groove, said rib having an upper surface engageable with said upper surface of the groove, thereby locking the nozzle in place on the receptacle, and said rib having a conical lower surface to facilitate attachment of the nozzle on the receptacle rim by pressing the nozzle thereon, thereby causing the conical surface to engage and slide over the rim and to mutually deform the nozzle and the receptacle rim to enable the rib to snap into the groove, and the circumferential edge of the rim portion of the receptacle being located inwardly of and engaged by the nozzle and being spaced inwardly of the contiguous outer surfaces of the nozzle and rim.

2. A closure structure for a receptacle for granular material, comprising at tapered nozzle having a larger opening at one end and means for securing it to the receptacle adjacent said large opening, means defining a smaller opening at the other end of said nozzle, said smaller opening being disposed in a plane forming an angle with the axis of said nozzle and having an outermost edge and an innermost edge, an inturned lip extending around the perimeter of said smaller opening an inturned wall portion on said nozzle adjacent the outermost edge of said smaller opening and forming an angle with the adjacent wall portion of the nozzle and defining a portion in said nozzle wherein material is entrapped when other material is being dispensed, a cap for said smaller opening, said cap including a planar body portion and a sealing rib projecting from said body portion and arranged to be received in said smaller opening, said sealing rib having an outwardly extending bead engageable with said rib of said smaller opening to removably secure said cap therein, and means connecting said cap to said nozzle including a boss extending laterally from said nozzle adjacent the lowermost portion of said inclined smaller opening, a recess formed in said boss opening at the upper surface of the boss, an elongated groove formed in each of a pair of opposite walls of said recess, a narrow extension formed integrally with said planar body portion of said cap, a boss extending downwardly from said extension having a shape and size corresponding substantially to said recess in said nozzle boss, and elongated beads formed on the opposite sides of said boss, said beads being engageable in the grooves in said recess walls and arranged to secure said cap to said nozzle with a securing force substantially greater than the force holding said cap in said nozzle opening.

3. A closure structure according to claim 2 wherein the narrow extension on said cap has a transverse groove formed therein to facilitate bending thereof to permit the cap to be removed from the nozzle opening.
